John Salisbur

UNITED STATES PATENT OFFICE.

JOHN SALISBURY, OF SCITUATE, RHODE ISLAND.

DESIGN FOR BOBBIN-SCORE.

Specification forming part of Design No. 5,052, dated June 27, 1871.

To all whom it may concern:

Be it known that I, JOHN SALISBURY, of Scituate, in the county of Providence and State of Rhode Island, have invented and produced a new and original Design for Scores inside of Spinning-Bobbins, of which the following is a specification:

The object of this design is to furnish an improved form of score for holding packings or springs into bobbins for spinning.

This design was used for illustrating a score in my application for Letters Patent on bobbins for

spinning, filed December 9, 1869, which was refused.

The bobbin B has the score C made in the form of a cone, with its base nearest and a little above the bottom of said bobbin.

I claim as my design—

The cone-shaped score C, as herein shown and described.

JOHN SALISBURY.

Witnesses:

JOHN H. CROWELL,
J. M. ADDEMAN.
